CLAIM

(21) Appl. No.: **29/431,230**

The ornamental design for a multi-compartment child care bag with a plurality of indicia containing pockets, as shown and described.

(22) Filed: **Sep. 5, 2012**

DESCRIPTION

(51) **LOC (9) Cl.** 03-01

FIG. 1 is a perspective view of a multi-compartment child care bag with a plurality of indicia containing pockets showing my new design;

(52) **U.S. Cl.**

FIG. 2 is a front view thereof;

USPC D3/232

FIG. 3 is a back view thereof;

(58) **Field of Classification Search**

FIG. 4 is a side view thereof;

USPC D3/232-233, 240-246

FIG. 5 is an opposite side view thereof;

See application file for complete search history.

FIG. 6 is a top view thereof;

(56) **References Cited**

FIG. 7 is a bottom view thereof;

U.S. PATENT DOCUMENTS

FIG. 8 is a perspective view with the top cut away showing the interior thereof; and,
